WILLIAM J. LAUSTERER, OF JAMESTOWN, NEW YORK, ASSIGNEE TO EMPIRE VOTING MACHINE COMPANY, OF ROCHESTER, NEW YORK, A CORPORATION OF NEW YORK.

VOTING-MACHINE.

995,357.

Specification of Letters Patent. Patented June 13, 1911.

Application filed October 9, 1905. Serial No. 281,875.

To all whom it may concern:

Be it known that I, WILLIAM J. LAUSTERER, of Jamestown, in the county of Chautauqua and State of New York, have invented certain new and useful Improvements in Voting-Machines; and I do hereby declare the following to be a full, clear, and exact description of the same, reference being had to the accompanying drawing, forming a part of this specification, and to the reference-numerals marked thereon.

This invention relates more particularly to a primary election lockout attachment whereby the ordinary voting machine can be converted into a machine for holding primary elections under such laws as have been enacted for instance for the holding of primary elections in Minnesota and Wisconsin. The leading feature of the primary election laws of these two States is as follows: All of the candidates of each party contesting in the primary election for the nomination by their party must file their names as such candidates with the properly designated officer and all of the candidates for all of the offices must then be printed on ballots, a separate ballot for the candidates of each party. In either State the voter can choose the party for whose candidates he will vote in the primary election, and having made his choice he must be restricted to the candidates of that party and must not be permitted to vote for the candidates of any other party, nor for any candidates not printed on his party's ballot. In Minnesota the voter must publicly declare his intention as to the party whose candidates he shall vote and the election officer must give him the ballot of the voter's party and must restrict him to voting on that ballot and prevent him from voting on any other. The ballot so voted will be folded and dropped into the box and on the counting of it, it will be apparent to the election officer whether the ballot is restricted to the candidates of a single party. In Wisconsin the voter is entitled to keep it secret as to which party he is to vote for and in that State the voter must be furnished with a ballot of each of the parties represented in the primary and the voter can then in the privacy of the booth mark the ballot of his choice and sepa-

rate it from the rest and vote it separately in the proper box, while the unvoted ballot must be cast in another box. If voting machines are used in the primary elections of either of these States they must correspond to the ballot practice above described, the names of all of the candidates of all of the parties that the voters of the precinct are entitled to vote on must be placed upon the machine and the machine must then be so adjusted that the candidates of but one party can be voted on by any one voter. In Minnesota where the voter must declare his intention as to the party of his choice, the election officer must set the machine accordingly to permit him to vote for the candidates of that party and for none other. In Wisconsin, however, where the voter is entitled to keep it secret as to which party he is to vote for, the machine must be left wholly unlocked so that the voter can start his voting on any of the parties, but having begun to vote on one party, the machine must then prevent him from voting for the candidates of any of the other parties.

The object of my invention is to provide a machine that will meet the requirements of the primary election laws of Wisconsin and Minnesota, especially in the important particulars above pointed out, and in such other particulars as will be described in the specification and pointed out in the claims.

In the accompanying drawings: Figure 1 is a rear view of the lower portion of the front plate of a voting machine of the type described in the Patent 849,123 to A. J. Gillespie and the Patents 793,666 and 820,802 to Lausterer. Figure 1^a is a front view of a portion of the plate or ballot board adapted for primary voting. Fig. 2 is a vertical transverse section of the line 2—2 of Fig. 1. Fig. 3 is a detail of one of the lockout bars. Fig. 4 is a detail of the guide for the lockout bars. Fig. 5 is a perspective view of the inspector's controlling lever, by which the locking out of all but the selected parts is secured in advance. Fig. 6 is a detail of the wire link connecting between the interlocking strap or the group of straps and the lockout bar. Fig. 7 is a side elevation of the wire link. Fig. 8 is a perspective view of a compensator used in the interlocking

in connection with this primary election lock-out. Fig. 9 is a side elevation of the compensator with the pivoted side shown in position for inserting the compensator of 5 the interlocking channel.

In this specification and the accompanying drawing, like numbers refer to like parts.

In the accompanying drawings reference numeral 1 refers to the face plate of the 10 machine as it is shown in Fig. 2. At the bottom of this plate is carried the interlocking channel 2 from which project the grouping pins 3 through suitable interlocking rollers 4 such as are illustrated in the patent 15 to Lausterer No. 793,666. Engaging with these interlocking rollers are wedges 5 carried by the interlocking straps 6. These straps 6, 6 are connected to the usual indicators 60 on the front plate 1 and are slotted 20 at 7 to permit the insertion therethrough of the resetting bar 8. They are also slotted at 9 to provide for the insertion of the muffling bar 10, and through the same slots are threaded the wire links 11, one of which is 25 shown in detail in Fig. 6, and in side elevation in Fig. 7. These links may be threaded each through a single strap or a single link may be threaded through two or more straps. The lower ends of links 11 are turned up 30 into loops 12 which loops may be passed through the slot 13 of the lockout bar 14 and may be spread sidewise to engage with the teeth 15, 15 on either side of said slot. Normally a single slot of this sort is provided 35 for each bar for each office line on the machine, and a single wire link may run from said slot to engage one or more of the interlocking straps of the particular office line to which that link is assigned. But I 40 may provide a plurality of slots in each bar for each office line so that a plurality of the wire links 11 from one office line may engage with one bar, and this arrangement has some advantages, in that it permits the more ready 45 transfer of the connections from individual straps from one of the lockout bars 14, 19, 20 or 21, to another bar, as different election ballots may make necessary. It will be noted that the connection between the interlocking straps or rods and the lockout bars, 50 is a loose one, the upper ends of the links sliding in the slots so that the bars and straps may move relatively independently. As usual the indicators are preferably arranged 55 to be freely moved to voted position or to be restored by the voter if a mistake is made, excepting for the limitations imposed by the party selecting device, but this may be reset in the manner hereinafter described if desired. These lockout bars, the 60 rearmost one being indicated by 14, are each carried on bell crank levers 15, 15 pivoted at 16, 16, said pivots being carried on the uprights 61 at one end and the bracket 17 at 65 the other end. Fastened to the lower ends of each of the bell cranks 15 are the connecting bars 18, 22, 23, 24. The lockout bars each have a vertical movement and rocks the long arms of the bell cranks 15 as they move upward, at the same time the short 70 arms of the bell cranks rock to the right uniformly, due to the connection between them of the bars 18, and in this way a simultaneous movement of both the lockout bars and the bars 18, 22, 23, 24 is secured. It 75 will be understood that the bars 19, 20 and 21 are similar to the bar 14, except as to the placing of the slots 13, and that these bars are each in turn supported by bell cranks 15, to which are connected respectively the 80 bars 22, 23 and 24. The intervals between lugs 15 are alike on all the bars, and while the distance between the centers is the same, they are placed at different distances from the end so that the wire links or their loops 85 that are connected to one bar will not interfere with the links connected to another bar. When a key is voted anywhere on the keyboard of the machine its interlocking strap rises and carries with it the wire link 11, 90 which in turn raises the bar 14, 19, 20 or 21 with which it happens to be connected. The raising of its lockout bar moves to the right as is shown in Figs. 1 and 5 the bar 18, 22, 23 or 24 connected therewith. The purpose 95 of my invention includes means which will prevent the raising of more than one of these lockout bars, and this is controlled in two ways, both of which I will now describe.

Secured to the bottom of the machine 25 100 is a bracket 26 at the right hand end, a similar bracket 27 at the left hand end. Mounted on each of these brackets for sliding movement is a similar bracket 28, which bracket has two slots therein 29, 30, through 105 which slots project the studs 31 and 32, which studs are mounted on the brackets 26 and 27. The slots 29 and 30 and the studs 31 and 32 form guides which limit and control the movement of bracket 28, permitting 110 the bracket 28 to be raised or lowered only to the extent to which the slots can move on the studs. Mounted on bracket 28 is a leaf spring 33 with two holes therein. When the bracket is in its lower position the upper 115 hole in the spring 33 engages with the stud 32 and locks the bracket 28 in its lowest position. When, however, it is in its elevated position, the lower hole engages with the stud 32 and locks it in its upper position. 120 Carried on the bracket 28 are interlocking pendants 34, in this case three of them being shown supported by each bracket swinging from the stud 35, the brackets 26 and 27 at 125 each end of the machine being alike in all of these particulars. These interlocking pendants 34 when the bracket 28 is in its lowest position swing immediately over the lockout bars 14, 19, 20 and 21. The lockout bars are held to a strictly vertical movement 130

by reason of the fact that they move in the recesses 36, 36 formed in the plate 37 shown in Fig. 4, one of which plates is carried on each of the brackets 26 and 27. When any 5 one of the lockout bars rise, the pendants are swung aside in the direction of the remaining bars, and they are of such thickness and are so adjusted that they will center themselves over the adjacent bars and prevent 10 them from rising, as long as the raised bar remains in its uplifted position. To release the lockout bars from the control of these interlocking pendants, the pendants may be lifted out of the way by raising the brackets 15 28, 28 which support them, in which case the lockout bars will be free to rise at both ends. The lockout bars are further controlled in their movement through the bars 18, 22, 23, and 24, and when the lockout bars 20 are raised, these bars are given an endwise movement to the right. Pivoted in the side of the machine is a lever 38, the pivot of which extends through the casing and has rigidly connected thereto the bracket 39, 25 which bracket has a slot 40 therein just wide enough to permit one of the bars 18, 22, 23, or 24 to enter therein by turning the pointer on the side of the casing to the number desired; the bar indicated by it will be left 30 free to move endwise and can be operated by any one of the keys on the machine connected to it, but the remaining bars will be held locked. If the pointer is turned to the mark "Closed", all of the bars will be 35 locked, and if turned to the mark "Open", all of the bars will be unlocked. For use in the Wisconsin primary elections where the voter is not permitted to announce his party affiliations, the pointer should be left in the 40 open position during the whole of the election, but in the Minnesota elections where the voter must announce his party affiliations, the pointer must be placed to indicate the party announced before the voter is permitted 45 to close the curtain. In primary elections when held under an Australian ballot law, the party levers on the machine are locked out of operation. Under the laws of either of the States referred to the voter 50 must vote for each candidate separately.

It may be stated, generally, that as there are usually at least two candidates contending for the nomination of each party, the grouping pins 3 between the adjacent office 55 groups, (which latter usually embody one vertical row of indicators only), are removed and these groups thereby extended to include at least two vertical rows of indicators, and compensators are employed, 60 so that in the enlarged group thus formed but one indicator may be moved to voted position. Or, if there are several candidates to be nominated, the grouping pins between as many adjacent groups as are combined, 65 are removed, and a sufficient number of

compensators inserted so that only the proper number of votes may be indicated in the enlarged group. Ordinarily but two or three parties will put candidates in nomination. The dominant party will always have the greatest number of candidates competing with each other for nomination, and the minor parties will have a correspondingly fewer number of candidates for nomination. Thus the Republican party 70 may have four candidates competing for the nomination for Congressmen. Only one of these can secure the nomination. The general necessities of all the candidates in the field may indicate that three of the party 75 lines on the machine shall be given to the Republican party candidates, and one party line to the Democratic candidate, and still another party line to the Prohibition candidate. If four candidates for Congress are 80 contending for the nomination in the Republican party and but three party lines are assigned to the Republican party, then these four candidates must be placed on two office lines, the grouping pins must be adjusted 85 to include the interlocking rods of two office rows, and a compensator must be inserted in the interlocking channel to prevent the voting of more than one key in these two office lines. If the Democratic 90 party has three candidates for the nomination and has but one part line assigned to it, then the candidates for this party must be spread on three office lines, and these same 95 three office lines must be included in the group for Congressmen in the balance of the parties as well. This would necessitate the use of two compensators in the interlocking channel in this particular group to prevent the voting of more than one key therein. 100 To permit the ready insertion or removal of these compensators I have invented a compensator of the form as shown in Figs. 8 and 9. This compensator is of the same thickness as an interlocking wedge and has on either side thereof a recess 41 which engages the upper part of the interlocking channel 2. The part 42 rests in the groove of the interlocking channel in contact with the interlocking rollers or with either of 110 the interlocking wedges that may have been voted adjacent to it. This compensator is composed of two pieces one of which is pivoted on the other and is capable of movement thereon. The part 43 shown in Fig. 8 is the larger piece and on it is pivoted the piece 44 shown in dotted lines in Fig. 9. When the part 44 is placed in the position shown in the dotted line the compensator 120 can be inserted directly into the channel, keeping it parallel to the grouping pins and rollers so that the part 42 can engage directly with the recess in the far side of the channel. After which the compensator can be lowered to position and then the part 44 125 130

can be turned from the dotted line to the vertical position making the engagement of the compensator complete. When the machine is converted from primary election to ordinary election, all these compensators must be removed from the channel, the brackets 28 must be placed in their elevated position and the indicating pointer 38 must be placed in its "Open" position. The 10 grouping pins, of course, should be placed in position corresponding to the ticket to be voted, and these changes will constitute all the changes that are necessary to convert the machine from its use in a primary election 15 to its use in an ordinary election. By reversing the process modified according to the needs of the primary election the machine is equally capable of being changed back from the regular election to the primary election.

In Fig. 5 I show a resetting lever 45 pivoted so as to engage with the bars 18, 22, 23 and 24 mounted so that its forward end will be accessible to a voter standing 25 in front of the machine so that if the voter has made a mistake in choosing the wrong party he can reset the lockout bar and start anew. This lever 45 engages in recess 46 in each of the bars 18, 22, 23 and 24 so that by 30 moving it to the left or to the dotted line position as shown in Fig. 5, the voter can recall his vote and take a fresh start. The indicator bars 6 are reset by the resetting bar 8 engaging therewith as usual in this 35 type of machine and the lockout bars 14, 19, 20 and 21 are correspondingly reset by brackets 50 secured to the main resetting bar and engaging their upper sides as shown in Fig. 1.

1. I claim as my invention:

1. The combination in a voting machine, of a plurality of indicators, a series of lockout bars, means for interchangeably connecting said indicators to said lockout bars, 45 thereby controlling said indicators through the latter and means operable independently of the indicators to prevent the operation of other indicators than those controlled by a predetermined bar.

2. The combination in a voting machine of a plurality of indicators, a series of lockout bars to which bars said indicators may be interchangeably connected, interlocking devices between said lockout bars for preventing 55 more than one of said bars and the indicators connected thereto occupying voted position at the same time, and means operable independently of the indicators for determining which of said bars can be placed in voted position.

3. The combination in a voting machine of a plurality of voting devices, separate independently movable lockout bars connected to said devices, and adapted to be moved edgewise thereby when any one of

the devices is moved into voted position, and means preventing more than one of said lockout bars from edgewise movement.

4. The combination in a voting machine of a plurality of series of voting devices, 70 lockout bars one connected to each of said series and adapted to be moved when said devices are moved into voted position, a means adjustable into coöperative relation with said bars to prevent more than one of 75 them from movement, and also adjustable to permit all of said bars to move.

5. In a voting machine, a combination of voting devices and interlocking mechanism therefor, controlling said voting devices by 80 offices, a supplementary interlock operable by the voting devices and controlling them by parties, said supplementary interlock being capable of movement into and out of operating position at will.

6. In a voting machine, the combination with a plurality of series of voting devices, and interlocking mechanism for said voting devices controlling the operation by offices, of a supplemental interlocking device oper- 90 able by the voting devices and controlling them by parties, and capable of being moved into operative relation with the voting devices when said machine is used in primary elections and out of operative relation when 95 said machine is used in general elections.

7. In a voting machine, the combination with a plurality of series of voting devices, a plurality of edgewise movable lockout bars, one for each series, links extending between the devices and the bars and having a loose connection with one of the parts to permit the movement of the bars independently of the devices, but to cause the positive operation of the bar when its voting devices 105 are moved and means for limiting the number of bars operable to unlocking position.

8. In a voting machine, the combination with a plurality of series of indicators, a plurality of lockout bars, one for each series 110 and operable to unlocking position by the movement of an indicator in the series, of a single indicating and locking device operable from the exterior of the machine and coöperating with the lockout bars to select 115 and indicate the particular bar that can be operated.

9. In a voting machine the combination with a plurality of lockout bars and a plurality of voting devices controlled by each 120 of a resetting bar for said voting devices, and means carried by said resetting bar to positively reset said lockout bars.

10. In a voting machine, the combination with a plurality of lockout bars and a series 125 of voting devices controlled by each, of a resetting bar moving parallel thereto, and means carried on said resetting bar for resetting said lockout bars.

11. In a voting machine, the combination 130

- with a plurality of lockout bars, of means carried on each bar to give to both ends of said bar an equal movement, and interlocking devices between said bars.
5. In a voting machine the combination with a plurality of lockout bars, and means for causing the uniform lateral movement of the latter, of a plurality of indicators connected to each of said bars at different portions of its length.
10. In a voting machine, the combination with a plurality of lockout bars, a series of voting devices operable upon and controlled by each, an interlocking mechanism preventing the operation of more than one of said bars, and a single indicating and locking device coöperating with said bars to select and indicate the particular bar that can be operated.
15. In a voting machine the combination with a plurality of lockout bars and bell cranks on which at two or more points in their length said bars are carried, of longitudinally moving bars to which said bell cranks are connected.
20. In a voting machine, the combination with a lockout bar and a bell crank connected to one arm thereof, of a governing bar connected to the other end of said bell crank, and means for locking said bar against movement.
25. In a voting machine the combination with a lockout bar and a plurality of bell cranks having one arm connected thereto, of a governing bar connected to other arms of said bell crank levers, and means for locking said bar against movement.
30. In a voting machine the combination with a plurality of bell crank levers arranged in series, and a lockout bar for the bell cranks of each series, said lockout bar being connected to one arm of the said bell cranks, of a governing bar for each lockout bar connected to the other arm of the bell cranks in each series, and means for moving the bell cranks.
35. In a voting machine, the combination with a plurality of series of indicators, a plurality of lockout bars one for each series, of means coöperating with and adjustable to different positions to control said bars, a movement to one position operating to lock all of said bars, into another position to lock all excepting one, and into a third position to permit the operation of all of them.
40. In a voting machine, the combination with a plurality of lockout bars, and interlocking devices therefor limiting the number of said bars to be operated, said interlocking devices being capable of adjustment into and out of coöperative relation with said bars for the purpose of limiting the number of said bars capable of operation or permitting their free movement.
45. In a voting machine for primary elec-
- tions, the combination with a plurality of voting devices grouped according to offices and according to parties, means for preventing the operation of the devices for more than a single party, of a single controlling device operable independently of the voting devices to either select the party whose indicators may be operated and lock out those of the remaining parties, or to leave the devices of all the parties open permitting the voter to select in secrecy the party whose devices may be operated.
50. In a voting machine the combination with a plurality of series of voting devices, each series being devoted to candidates of a particular party, of a single means operable to one position to lock the devices of all the parties, to another to lock all of those excepting one, and to a third position to permit the operation of any of them.
55. In a voting machine, the combination with a plurality of series of indicators, of a plurality of lockout bars, one for each series, and an interlocking device for limiting the number of said bars that can be operated, said device being capable of occupying two positions, one for properly interlocking the bars, and the other for completely disengaging said lockout bars.
60. In a voting machine interlocking mechanism, the combination with a support, a frame movable thereon, and a series of interlocking pendants suspended therefrom, said frame with its pendants being capable of occupying a raised or lowered position, means for locking said frame in either position, and voting devices for coöperating with the pendants.
65. In a voting machine, the combination with voting devices, of a support and a frame mounted slidably thereon, a stud fastened to said frame, and interlocking pendants mounted on said stud and coöperating with the voting devices.
70. In a voting machine, the combination with voting devices, of a support having studs thereon, a sliding frame mounted on the support engaging with said studs, a stud carried by said frame and interlocking pendants carried on said stud and adapted to coöperate with the voting devices.
75. In a voting machine the combination with voting devices, of a bracket having studs thereon, a standard having slots engaging with said studs and the spring on said standard having a plurality of holes therein to engage with one of said studs for the purpose of locking said standard in a plurality of positions with reference to said stud and its bracket.
80. An interlocking block for a voting machine composed of two pieces pivoted together.
85. In a voting machine, the combination with a grooved interlocking channel, of a

- collapsible interlocking block engaging therewith capable of collapsing for insertion into and of being spread to engage with the walls of said channel.
- 5 29. In a voting machine, the combination with the interlocking channel, of an interlocking block formed of two pieces pivoted together, one of said pieces engaging with one side of said channel, both of said pieces 10 engaging with the other side of said channel.
30. In a voting machine lockout, the combination with a series of bars operable by the voting devices, of a lever controlling said bars, having a handle projecting outside 15 the casing of the voting machine, a slot in said lever to permit the entrance of one bar only, said lever being movable to bring the slot opposite to each bar in turn, to unlock it.
31. In a voting machine, the combination 20 with a series of lockout bars operable by the voting devices, of a lever controlling said bars and having a slot therein to permit a single bar to enter, said lever being movable to bring said slot opposite to each bar in 25 turn.
32. In a voting machine, the combination of a series of lockout bars and voting devices for operating them, of a movable abutment for controlling said bars, having a slot 30 therein sufficient to permit the movement of one bar at a time, said abutment being movable with relation to the bars to unlock each of them or to lock all of them, or to permit 35 free movement of all of said bars and an indicator connected thereto to show the position of said abutment.
33. The combination in a voting machine of a plurality of series of voting devices arranged in office and party rows extending at an angle to each other, of a plurality of 40 edgewise movable lockout bars one connected to each series extending parallel with the party rows and means for preventing the movement of more than one of said bars laterally of said rows. 45
34. A voting machine adapted for use in general elections, comprising a plurality of individual candidate voting mechanisms, means for locking out the voting mechanism to prevent general voting and means for 50 releasing a given number of said mechanisms to permit primary voting.
35. In voting machines, the combination with the series of voting mechanisms arranged in groups representing different 55 party tickets, of a member shiftable to different extents to lock out all but one of said groups.
36. In voting machines, the combination with the series of voting devices arranged 60 in groups representing different party tickets, and with operating and restoring mechanism for said devices, of a member shiftable to different extents and operative to lock out all but a selected one of said groups, 65 whereby the machine may be set for primary voting.
